ORVILLE PENDELL INVENTOR.

BY

Richard B. Deven

ATTORNEY.

Patented June 1, 1926.

UNITED STATES PATENT OFFICE.

ORVILLE PENDELL, OF SCHENECTADY, NEW YORK, ASSIGNOR TO PENDELL BOILER COMPANY, OF RICHMONDVILLE, NEW YORK, A CORPORATION OF NEW YORK.

FIRE POT.

Application filed October 27, 1920. Serial No. 419,856.

This invention relates to furnaces and more particularly to fire pots and has for its primary object to improve upon the structure of fire pots as shown in Letters Patent No. 1,279,419 issued to me September 17, 1918.

Another object of the invention is to provide an improved fire pot to be used in conjunction with a boiler structure disclosed in said Letters Patent, constructed in a manner to permit the circulation of water through the fire pot whereby heat will be absorbed from the burning fuel in a manner to secure the best possible efficiency.

A further object of the invention is to generally improve upon furnaces and fire pots therefor by providing an improved structure which will be simple, yet efficient in operation, well adapted for the purpose designed and which may be manufactured at a comparatively low cost.

In order that those skilled in this art may have a full understanding of the invention, I have illustrated a desirable and preferred embodiment of the same in the accompanying drawing forming a part of this specification, and throughout the various views in which like reference characters refer to the same parts.

In the drawing:—

Figure 1 is a side elevation of the fire pot showing the boiler construction fragmentarily.

Figure 2 is a top plan view of the fire pot.

Figure 3 is a top plan view of the bottom ring.

Figure 4 is a top plan view of the first from the bottom ring.

Figure 5 is a top plan view of the second from the bottom ring.

Figure 6 is a top plan view of the third from the bottom ring, and

Figure 7 is a top plan view of the top ring.

The fire pot about to be described may be used with a boiler construction of conventional form but is especially adapted to be used with a boiler structure such as is illustrated in Letters Patent No. 1,279,419 which is provided with the legs 10 circumferentially spaced from the casing of the furnace and suitably spaced from each other. The preferred form of the present fire pot consists of a plurality of parallel

superimposed hollow rings. The bottom ring 11 is provided with the water inlets 12 extending in the same plane of the ring and provided with the upstanding members 13 for receiving the pipes 14 leading into the legs 10. The first from the bottom ring 15 shown particularly in Figure 4 of the drawing is provided with openings 16 upon its upper and lower side and also with the diametrically opposed elbows 17. The ring 11 is also provided with openings 18 and the openings 18 and 16 from the bottom of the ring 15 are in communication with each other through suitable nipples 19. The elbows 17 are communicated with the legs 10 of the boiler structure by means of pipes 20. The second from the bottom ring 21 as shown particularly in Figure 5 of the drawing is provided upon its upper and lower portions with openings 22 for receiving the nipples 19 and is also provided with diametrically opposed elbows 23 which are communicated with the legs 10 by means of the pipes 24. The third from the bottom ring 25 is provided with the top and bottom openings 26 and the diametrically opposed elbows 27 which communicate with the legs 10 through the pipes 28. The openings 26 receives the nipples 19 so that this ring 25 will be in communication with the top ring and the ring immediately below namely ring 21. The top ring 29 shown particularly in Figure 7 of the drawing is provided with openings on its bottom portion for receiving the nipples 19 and has the diametrically opposed elbows 30 and also an additional elbow 31 which are suitably communicated with the legs 10 through the pipes 32. It will, of course, be understood that any suitable grate may be placed in the fire pot. The heat of the burning fuel in the fire pot is transmitted through the various rings thereby causing circulation of the fluid contained therein, whereby the water will be circulated upwardly into the boiler structure and it will be seen that the greater portion of the heat is abstracted from the gases of combustion before they can effect an exit from the furnace structure and that the greater portion thereof will come into contact with the hollow rings before passing upwardly to escape from the furnace. It will be obvious that this fire pot will be applicable to furnaces of various constructions and I have merely

described same in connection with the boiler construction shown in Letters Patent 1,279,419 for convenience. Other usages and advantages of this fire pot will readily occur to those skilled in the art to which this invention appertains.

Obviously, the invention is not limited and restricted to the precise, and exact details of construction as illustrated and described, because it is susceptible of a variety of embodiments, and many minor mechanical changes may be made in such preferred incorporation of the invention without departing from the substance or 10 essence of the invention and without the sacrifice of any of its substantial benefits 15 and advantages.

Having thus fully described my invention what I claim as new and desire to secure by Letters Patent is:—

In combination with a boiler, a fire pot comprising a plurality of superimposed hollow rings disposed in parallel relation with each other, the lowermost ring having 20 water inlets, each ring provided with openings, nipples connecting openings of each ring with openings of the next ring above the same, elbows disposed in pairs on each ring so as to be diametrically disposed from each other and means for communicating 25 the elbows with the boiler.

In testimony whereof I affix my signature.

ORVILLE PENDELL.
